(57) **CLAIM**

An ornamental design for a multifunction inkjet printer, substantially as shown and described.

DESCRIPTION

FIG. 1 is a perspective view of a multifunction inkjet printer, in accordance with the present invention;

FIG. 2 is a front view thereof;

FIG. 3 is a left view thereof;

FIG. 4 is a right view thereof;

FIG. 5 is a top view thereof; and,

FIG. 6 is a rear view thereof.

The broken lines are for illustration only and form no part of the claimed design.
